United States Patent Office.

JULIO H. RAE, OF SYRACUSE, NEW YORK.

Letters Patent No. 66,389, dated July 2, 1867.

IMPROVED ICE-CREAM FREEZER.

The Schedule referred to in these Letters Patent and making part of the same.

TO ALL WHOM IT MAY CONCERN:

Be it known that I, JULIO H. RAE, of Syracuse, in the county of Onondaga, in the State of New York, have invented a new and useful Improved Ice-Cream Freezer; and I do hereby declare that the following is a full, clear, and exact description thereof, which will enable those skilled in the art to make and use the same, reference being had to the accompanying drawing, forming part of this specification, in which drawing—

Figure 1 represents a vertical central section of this invention when the same is ready for operation.

Figure 2 is a horizontal section of the same.

Figure 3 is a section of the can after the freezing operation has been completed.

Similar letters indicate corresponding parts.

This invention relates to an ice-cream freezer in which an internal freezing-surface is created by a cylinder which rises from the bottom of the can, and which is open at the top to receive the pounded ice or freezing-mixture, and also open at the bottom to allow the water resulting from the melting of the ice to run off, said bottom A' being elevated above the bottom edge of the can to provide for a free escape of the water. The internal freezing-cylinder forms the guide of the beater, which is provided with two vertical slats at different distances from the centre of rotation, and with two spring scrapers, one to clean the outer surface of the inner freezing-cylinder, and the other to clean the inner surface of the can. The pounded ice is introduced into the inner freezing-cylinder through a funnel which, when reversed, forms the cover for the can, so that when the freezing operation has been completed, the can can be readily covered up and the ice-cream protected against the influence of the atmosphere, or against impurities or insects.

A represents a can, which is made of tinned sheet iron, or of any other suitable material, which, however, must be a good conductor of heat. This can is cylindrical or conical, and from the centre of its bottom rises a hollow cylinder, B, which is open at the top, to receive a quantity of pounded ice or of any suitable freezing-mixture, and which is also open at the bottom, so that the water resulting from the melted ice is free to run off and the full effect of the freezing-mixture is obtained. The bottom A' of the can is elevated above the bottom edge thereof, so that the water can run off without obstruction, and by these means an internal freezing surface is created which materially facilitates the freezing operation. The can A is placed in a tub, which is packed with ice or a suitable freezing-mixture in the ordinary manner, and it is provided with a beater, C, composed of two horizontal arms, a, which are provided with eyes to drop over the internal freezing-cylinder B, and the ends of which are connected by vertical slats b b', situated at different distances from the centre of rotation of the beater. These slats are provided with spring scrapers c c', one of which bears against the outer surface of the inner freezing-cylinder, while the other bears against the inner surface of the can, and as the beater revolves said spring scrapers keep the surfaces against which they bear clean and free from ice, which would otherwise be liable to adhere to them and to reduce the effect of the freezing-mixture or of the ice in the inner freezing-cylinder and in the space round the can. The revolving motion of the beater is effected by bevel-wheels f g, one of which is attached to the upper arm of the beater, and the other to a horizontal shaft, h, which has its bearings in a standard, i, secured to the supplementary cover D. The wheel f is provided with a central hole, the diameter of which corresponds to that of the interior diameter of the cylinder B, and from the supplementary cover rises a bracket, i', which is bored out to receive the spout of the funnel-cover E. Through this funnel the pounded ice or freezing-mixture is introduced into the inner freezing-cylinder, and after the freezing operation has been completed the supplementary cover D, together with the beater, is removed, and the funnel-cover is inverted and placed upon the can, the end of the spout being stopped up by a plug or cap, so that said funnel-cover forms a protection for the contents of the can.

I am aware that an ice-cream freezer has been made in which a hollow shaft was used to create an additional internal freezing-surface, but this shaft was closed at the bottom, and the water resulting from the melted ice soon filled up the hollow shaft, and thereby the freezing effect was materially reduced. I do not claim broadly, therefore, an ice-cream freezer with an internal freezing-surface, but what I claim as new, and desire to secure by Letters Patent, is—

1. The combination of the open cylinder B and raised bottom A' of the can A, substantially as described, for the purpose specified.
2. The beater C, with double spring scrapers c c', in combination with the can A and internal cylinder B, constructed and operating substantially as and for the purpose set forth.
3. The funnel-cover E, in combination with the can A and internal cylinder B, constructed and operating substantially as and for the purpose described.

JULIO H. RAE.
